MATERIAL HANDLING APPARATUS

Ray C. Kivley, Oak Park, Ill., assignor to Western Electric Company, Incorporated, New York, N. Y., a corporation of New York

Application September 16, 1937, Serial No. 164,165

1. Claim. (Cl. 266—6)

This invention relates to material handling apparatus, and more particularly to apparatus for quenching parts which have been galvanized.

It is an object of the present invention to provide a simple and safe apparatus for handling articles.

In accordance with one embodiment of the invention, there is provided a device for quenching articles of hardware after they have been passed through a galvanizing bath, which comprises a tiltable basket-receiving framework for receiving a basket in which articles have been carried during their immersion in a galvanizing bath, which framework carries a trough-like member for directing the parts from the basket, when the framework is tilted, into a perforated receptacle immersed in a quenching bath. The receptacle is pivotally mounted so that it may be rocked out of the quenching bath to dump the quenched parts onto a platform for direction to a suitable tote pan or similar device. The tiltable receptacle is arranged to be driven through a bell crank lever which is operative when the tiltable framework is in a predetermined position and inoperative when the tiltable framework is in any other position.

A better understanding of the invention will be had by reference to the following detailed description when considered in conjunction with the accompanying drawings, wherein

Fig. 1 is a plan view of a quenching tank for use in a hardware galvanizing process;

Fig. 2 is an enlarged side elevational view of the structure shown in Fig. 1, parts being broken away to more clearly illustrate the structural features of the apparatus;

Fig. 3 is an enlarged fragmentary elevational view showing the tiltable framework and taken substantially along the line 3—3 of Fig. 1 in the direction of the arrows;

Fig. 4 is a fragmentary sectional view taken along the line 4—4 of Fig. 3 in the direction of the arrows; and

Fig. 5 is a circuit schematic showing the electrical control for the tiltable receptacle.

Referring now to the drawings, wherein like reference characters designate the same parts throughout the several views, the numeral 10 designates generally a sheet iron framework composed of side plates 11 and 12, end plates 13 and 14, an intermediate plate 15 and a top plate 16. The top plate 16, as clearly shown in Fig. 2, slants downwardly to the right end (Figs. 1 and 2) of the framework 10 and is provided with a plurality of apertures 18 at its lower end, the

purpose of which will become apparent as the description progresses.

The side plate 12 is cut away, as shown at 19, (Fig. 2) and has fixed thereto a pair of plates 20 and 21, which extend outwardly from the plate 12. A pair of bearings 22 and 23 are mounted upon the plates 20 and 21, respectively, for rotatably supporting a shaft 24, to which there is fixed an angle iron framework 25, the horizontally extending portion of which is V-shaped 10 in configuration and the vertically extending portion of which is secured to the shaft 24. At the apex of the V-shaped portion of the framework 25, there is pivotally mounted a latch member 26 adapted to secure a galvanizing basket 27, shown 15 in dot and dash lines of Fig. 3, in place with its bottom resting upon the V-shaped portion and its left edge engaging the horizontal portion of the framework 25 so that the basket will not fall off of the framework 25 when the framework is tilted to dump parts which have been galvanized out of the basket 27 onto a chute 28 fixed to the shaft 24 by plate members 29 and 30 for directing the galvanized parts into a perforated receptacle 35 partially immersed in a 20 quenching bath 36 contained in that portion of the framework 10 bounded by the side plates 11 and 12, end plate 13, and intermediate plate 15. 25

The receptacle 35 is formed of a pair of side plates 40 and 41, substantially trapezoidal in shape, a perforated bottom portion 44, which is bent at 45 and has an upwardly slanting portion 46 extending from the bent portion to its junction with the side plate 40 and perforated end plates 47 and 48. The receptacle 35 is reinforced 30 at the juncture of the end and side plates by angle iron members 53 and 54 and at the upper and lower portions by angle iron members 55 and 56, respectively. The upper angle iron members 55 have a pair of upwardly extending arms 42 and 43 secured thereto. When the receptacle 35 is in the position shown, it rests upon a channel iron member 57, which is bent to conform to the bottom 44 to support the bottom when parts are dumped from the basket 27 into the receptacle 45 and guided by the side walls 47 and 48 and the portion 46 of the bottom 44 into the lower end of the receptacle. 40

The receptacle 35 is fixed to a shaft 60 by means of projections 61 and 62 formed integral 50 with the arms 42 and 43, which have a pair of plates 58 and 59 fixed thereto for guiding parts dumped from the receptacle toward the center of the plate 16. The shaft 60 is rotatable in a pair of bearings 63 and 64 and is adapted to be 55

oscillated by means of a link 65 pivotally attached at 66 to a portion of the end plate 41 and adapted to be driven by a crank 67 keyed to a shaft 68 of a gear reducer 69. The gear reducer 5 is mounted within the framework 10 and is adapted to be driven by a motor 70 mounted adjacent thereto and adapted to be supplied with current from a suitable source of supply 71 (Fig. 5) upon closure of a manually operable key 72.

10 The liquid forming the quenching bath 36 is fed into the tank portion of the framework 10 through a feed pipe 75 and the level thereof is maintained constant by the height of an outlet pipe 76.

15 Positioned directly beneath the apertures 18 of the plate 16 is a trough 77 having a drain pipe 78 interconnecting its lowermost portion with the outlet pipe 76 so that any excess of the quenching bath remaining on the galvanized 20 parts after they are removed from the bath will be directed to the outlet pipe 76 before the parts are directed into a container 79 supported by a shelf 80 fixed to the end plate 14.

An extending portion 85 of the shaft 24 passes 25 through the plate 20 and carries a contact actuating arm 86 which, when the tiltable framework 25 is in the position shown, will maintain a pair of contacts 87 closed (Fig. 5) but which will permit the contacts 87 to open when the framework 30 is tilted out of the position shown.

A more complete understanding of the invention will be had by reference to the following brief description of the operation thereof. After parts have been dipped in a galvanizing bath 35 while in the basket 27, they may be transported in any suitable manner, not shown, to the quenching apparatus forming the subject matter of this application and deposited on the framework 25 where the basket, which is provided with 40 a ridge 87, will be latched to the framework 25 by means of the latch member 26 and the basket tilted to dump the parts therefrom onto the trough 28, which will direct the parts into the receptacle 35. After the parts have thus been 45 quenched in the quenching bath 36, which penetrates into the basket 35 through the apertures

in the bottom 44 and end plates 47 and 48, the parts may be dumped from the receptacle 35 onto the top plate 16, which will direct them to a container 79. The tilting of the framework 25 is done manually; however, the tilting of the receptacle 35 is done by closing the manually operable key 72 to supply current from the source of supply 71 to the motor 70, suitable interlocking members, not shown, being provided to cause the motor to run until one complete revolution 10 of the shaft 68 of the gear reducer 69 has taken place. However, if the framework 25 is out of its normal position, as shown in Figs. 1, 2 and 3, the circuit to the motor 70 will be broken at the contacts 87 and the quenching receptacle 35 will not 15 be operated until the framework 25 is returned to its normal position, thereby preventing accidental operation of the receptacle 35, which might injure the operators or the apparatus. Although a specific embodiment of the invention has been 20 shown and described herein, it will be understood that numerous modifications and alterations could be made in the apparatus without departing from the scope of the invention, which is to be limited only by the scope of the appended 25 claims.

What is claimed is:

Quenching apparatus for use in conjunction with galvanizing processes comprising means for receiving a supply of quenching material, a receptacle normally held in a horizontal position and partially immersed in said quenching material, a tiltable basket supporting framework normally held in a horizontal position to receive a basket full of parts to be quenched and tilt- 35 able to dump the contents of a basket into the receptacle, motor driven means for tilting the receptacle from its normal horizontal position to empty quenched parts from it, and an electrical interlock in the motor circuit operable under 40 control of the tiltable framework for opening the operating circuit of the motor when the framework is tilted to prevent tilting of the receptacle when the framework is out of its normal position.

RAY C. KIVLEY.
